UNITED STATES PATENT OFFICE.

JAN NIEMCZYK AND WAWRZYNIEC WAWRZYNSKI, OF IRVINGTON, NEW JERSEY.

DESIGN FOR A MULTIPLE DISPLAY APPARATUS.

Application filed February 7, 1928. Serial No. 25,257. Term of patent 3½ years.

To all whom it may concern:

Be it known that we, JAN NIEMCZYK and WAWRZYNIEC WAWRZYNSKI, both citizens of Poland, and residing at Irvington, county of Essex, and State of New Jersey, have invented a new, original, and ornamental Design for a Multiple Display Apparatus, of which the following is a specification, reference being had to the accompanying drawing, forming part thereof.

The figure is a perspective view of a multiple display apparatus, showing our new design.

We claim:—

The ornamental design for a multiple display apparatus, as shown.

JAN NIEMCZYK.
WAWRZYNIEC WAWRZYNSKI.
